By his Att'y,

Inventor:
Edward O. Tinsley.
J. H. Richard

UNITED STATES PATENT OFFICE.

EDWARD O. TINSLEY, OF BROOKLYN, NEW YORK, ASSIGNOR TO ROBERT GAIR COMPANY,
OF BROOKLYN, NEW YORK, A CORPORATION OF NEW YORK.

COLLAPSIBLE CONTAINER.

1,296,140.

Specification of Letters Patent.

Patented Mar. 4, 1919.

Application filed June 17, 1918. Serial No. 240,380.

To all whom it may concern:

Be it known that I, EDWARD O. TINSLEY, a citizen of the United States, residing in borough of Brooklyn, in the county of Kings 5 and State of New York, have invented certain new and useful Improvements in Collapsible Containers, of which the following is a specification.

My invention relates to a collapsible container or carton adapted to be made of cardboard, pasteboard, paper or other suitable material.

One of the objects of my invention is to provide a container which may be more economically manufactured and more readily shipped than the tin tobacco-containers now in well known use, which adapts itself very readily to the present type of tobacco-can filling machines.

Another object of my invention is to provide an improved closure at one end of the container, which closure may be operated by the action of a single finger, and may be folded inwardly to form a closure and outwardly to form a pouring spout for the tobacco.

Another object of my invention is to provide a container adapted to be made from a single blank of cardboard or the like, with only one glued portion therein, and adapted after the container has been formed and glued, to be folded and shipped flat to the tobacco manufacturing or filling establishment, after which it may be easily opened 35 to carton form by a single motion ready for filling and closing in the usual manner.

Obviously, the exterior faces of the container may be ornamenteally printed upon for the purpose of advertising and the like to 40 the same extent as it is now done in the case of well known tobacco containers; and this printing may take place before or after the blanks are cut or after they are assembled and folded.

While herein, I have described the details of my invention, it is particularly noted that the invention is not limited to these, since the construction of the container may be greatly varied without departing from the 45 spirit and scope of the invention as claimed.

In the accompanying drawing showing by way of example, one of many possible embodiments of the invention,

Figure 1 is a perspective view of the container closed;

Fig. 2 is a perspective view of the container with the pouring closure nearly open;

Fig. 3 is a fragmental perspective view showing the pouring closure closed, but with the sealing flap of the container opened;

Fig. 4 is a sectional view taken on the line 4—4 of Fig. 1;

Fig. 5 is a face view of one of the blanks from which the containers are constructed;

Fig. 6 is a face view of a container folded flat for shipment; and

Fig. 7 is an end view of the container folded nearly flat as in Fig. 6.

Owing to the use to which my container is to be put, it is desirable to conserve the 70 moisture of the contents thereof. Therefore, it is desirable that the cardboard be internally paraffined or otherwise treated for making the same moisture proof; but the invention is not limited to moisture proof 75 material, since the carton may be used for many purposes other than for tobacco.

The blank 5 (Fig. 5) is provided with a plurality of longitudinal scorings 6, 7, 8, 9, 10 and 11 dividing the blank into a back 80 portion 12, an outer front portion 14, an inner front portion 15, an outer connecting side portion 16, an inner connecting side portion 18, and outer and inner side edge portions 19 and 20. When the container is assembled, the inner side edge portion 20, has its outer face disposed against the inner face of the outer connecting portion 16; the inner face of the outer front portion 14 is disposed against the outer face of the inner 90 front portion 15, and the inner face of the outer edge portion 19 is disposed against and glued to the outer face of the inner connecting portion 18. This glue is indicated by the diagonal lines 21 and 22.

The pouring closure 25 is provided with vertical scorings 26 and 28 and diagonal scorings 29 dividing the closure into end sections 30, a middle section 31, and triangular sections 32 connecting the end sections with 100 the middle section. The pouring closure forms extensions of the inner portions 15, 18, and 20 and is separated therefrom by means of a horizontal scoring 33. A slight pressure upon the outer face of the middle 105 section 25, causes the same to fold inwardly, the triangular sections 32, automatically folding downwardly over the middle section, and the end sections in turn folding over the triangular sections as indicated in Fig. 2. 110

The sealing flap 35 extends from the upper edge of the back portion 12, and is separated therefrom by means of a scoring 36, and is divided by a scoring 38 into a cover portion 39, and a tucking portion 40. When the sealing flap is in sealed position as shown in Fig. 1, the cover portion 39, lies over the pouring closure 25 holding the same folded, while the tucking portion is tucked between the upper part of the outer and inner front portions 14 and 15.

Inwardly folding tabs 42 extend from the lower edge of the inner side members and are separated therefrom by a securing line 43 which also forms a line of connection between the intermediate cover flap 44 extending from the lower edge of the inner front portion 15. When the tabs 42 are folded inwardly, as shown in Figs. 1 and 2, the cover flap 44 is disposed thereover and is held in place by the folding tab 45 extending from the lower edge of the back portion and provided with scorings 46 and 48 dividing the folding flap into an intermediate portion 49 covering the cover flap, and a tucking portion 50 adapted to be tucked between said portions 14 and 15.

When the middle and triangular sections 31 and 32 of the pouring closure are opened outwardly so that the scorings 26 and 28 are in alignment with the scoring lines 6 and 7 the container may be folded along one of said lines so that the inner connecting portion 18 may lie against the back portion 12 and the inner edge portion 20 against the inner front portion (Fig. 6), the container folding along the scoring lines 7 and 9 as shown. It is obvious, however, that the container could be in like manner folded along the scorings 8, 6 and 10. When thus folded, the containers may be packed for shipping in bulk. When the package is to be filled, the tabs 42, the cover flap 44 and the folding flap 45, are closed as in Fig. 1; and the sealing flap 35 and the pouring closure 25 are opened out to their fullest extent somewhat more than is illustrated in Fig. 2. The package is then filled by hand or machine in the usual manner, and the pouring closure 25 folded to the position of Fig. 3, whereupon, the sealing flap 35 is tucked in the tucking space between the outer and inner front portions 14 and 15, after which, the container may be sealed, as for instance, by means of a revenue stamp or in some instances by placing a small amount of glue on the upper sealing flap. When it is desired to pour the contents from the container, the upper sealing flap is opened as in Fig. 2 by movement of the finger; and the natural resiliency of the material causes the pouring closure 25 to rise slightly, somewhat as indicated in Fig. 2, after which a touch of the finger will cause it to straighten out, and form a pouring

spout for pouring the contents from the container. A single touch of the finger is all that is necessary to force the middle section 31 inwardly and downwardly, whereupon, the triangular sections 32 and the end sections 30 automatically fold down almost to the position of Fig. 3, and are completely folded down when the sealing flap 35 is inserted as shown in Fig. 1.

It will be observed that the container is formed of a single blank which substantially forms an inner box and an outer box, thus making the container strong in construction and practically moisture proof.

I claim:

1. A collapsible container comprising, when in containing position, an outer front portion and an inner front portion, a back portion, outer side portions and inner side portions, a top closure, and a bottom closure, the top closure providing when open a spout for the container and being formed by an extension of the inner front portion and inner side portions of the container; said container being formed from a blank consisting of a central portion and two wings, one of the wings being of greater length than the other and the central portion being of greater length than the longer wing, the shorter wing being scored for folding longitudinally near the edges, the central portion being scored longitudinally at the edges and transversely near the ends, and the longer wing being scored longitudinally near the edges and transversely near the lower end and transversely and diagonally near the upper end.

2. A collapsible container comprising, when in containing position, an outer front portion and an inner front portion, a back portion, outer side portions and inner side portions, a top closure, and a bottom closure, the top closure providing when open a spout for the container and being formed by an extension of the inner front portion and inner side portions of the container; said container being formed from a blank consisting of a central portion and two wings, one of the wings being of greater length than the other and the central portion being of greater length than the longer wing and narrower than either wing, the shorter wing being scored longitudinally near the edges, the central portion being scored longitudinally at the edges and transversely near the ends, and the longer wing being scored longitudinally near the edges and transversely near the lower end and transversely and diagonally near the upper end.

3. A blank for a collapsible container consisting of a rectangular central portion and two rectangular wings, one of the wings being of greater length than the other and the central portion being of greater length

than the longer wing and narrower than either wing, the shorter wing being scored longitudinally near the edges, the central portion being scored longitudinally at the 5 edges and transversely near the ends, and the longer wing being scored longitudinally near the edges and transversely near the lower end and transversely and diagonally near the upper end, to form by folding 0 a container of box form having an outer front portion and an inner front portion, a back portion, outer side portions and inner side portions and a bottom and a top closure, the top closure being foldable and 5 operating in three directions.

4. A blank for a collapsible container consisting of a rectangular central portion and two rectangular wings, one of the wings being of greater length than the other and 0 the central portion being of greater length than the longer wing and narrower than either wing, the shorter wing being scored longitudinally near the edges, the central portion being scored longitudinally at the 5 edges and transversely near the ends, and the longer wing being scored longitudinally near the edges and transversely near the lower end and transversely and diagonally near the upper end, to form by folding 0 a container of box form having an outer front portion and an inner front portion having space between them at the upper edges, a back portion, outer side portions and inner side portions, a covering flap insertible in 15 the space between the outer and inner front portions, and a bottom and a top closure, the top closure being foldable and operating in three directions.

5. A collapsible container consisting of 10 a single blank comprising a back portion; outer and inner front portions; outer and inner connecting side portions respectively connecting the outer and inner front portions with the back portion; outer and inner side edge portions respectively connected to the outer edges of the outer and inner front portions, the outer edge portion being glued to the outer face of the inner connecting portion, the inner edge portion lying 15 against the inner face of the outer connecting portion; a pouring closure scored to form a middle section and end sections respectively forming continuations of said inner front portion and said inner side portions, and triangular sections connecting the middle sections to the end sections; said sections being adapted to be disposed in the planes of said inner portions respectively, and to fold inwardly, with the triangular 10 sections on the middle section and under the respective end sections; a sealing flap extending from the upper edge of the back portion and comprising a cover portion for covering said sections and a tucking portion adapted to be inserted between said front portions; inwardly folding tabs extending from the lower edges of the respective inner side portions; an intermediate cover flap extending from the lower edge of the inner front portion and folding over said tabs; and a folding flap extending from the lower edge of the back portion and comprising an intermediate portion covering the cover flap, and a tucking portion adapted to be tucked between said front portions.

7. A collapsible container consisting of a 105 single blank comprising a back portion; outer and inner front portions; outer and inner connecting side portions respectively connecting the outer and inner front portions with the back portions; outer and inner side edge portions respectively connected to the outer edges of the outer and inner front portions the outer edge portion being glued to the outer face of the inner connecting portion, the inner edge portion lying 110 against the inner face of the outer connecting portion; inwardly folding tabs extending from the lower edges of the respective inner side portions; an intermediate cover flap extending from the lower edge of the inner front portion and folding over said tabs; a folding flap extending from the lower edge of the back portion and comprising an intermediate portion covering the cover flap, and a tucking portion adapted 115 to be tucked between said front portions; and means for closing the upper part of the container.

8. A collapsible container comprising a 120 back portion; outer and inner front por-

15 adapted to be inserted between said front

portions and means for closing the lower part of the container.

6. A collapsible container consisting of a single blank comprising a back portion; outer and inner front portions; outer and inner connecting side portions respectively connecting the outer and inner front portions with the back portions; outer and inner side edge portions respectively connected to the outer edges of the outer and inner front portions the outer edge portion being glued to the outer face of the inner connecting portion the inner edge portion lying against the inner face of the outer connecting portion; a pouring closure scored 80 to form a middle section and end sections respectively forming continuations of said inner front portion and said inner side portions, and triangular sections connecting the middle sections to the end sections; said sections being adapted to be disposed in the planes of said inner portions respectively and to fold inwardly with the triangular sections on the middle section and under the respective end sections; a sealing flap extending from the upper edge of said back portion and comprising a cover portion for covering said sections and a tucking portion adapted to be inserted between said front portions; inwardly folding tabs 85 extending from the lower edges of the respective inner side portions; an intermediate cover flap extending from the lower edge of the inner front portion and folding over said tabs; and a folding flap extending from the lower edge of the back portion and comprising an intermediate portion covering the cover flap, and a tucking portion adapted to be tucked between said front portions.

7. A collapsible container consisting of a 105 single blank comprising a back portion; outer and inner front portions; outer and inner connecting side portions respectively connecting the outer and inner front portions with the back portions; outer and inner side edge portions respectively connected to the outer edges of the outer and inner front portions the outer edge portion being glued to the outer face of the inner connecting portion, the inner edge portion lying 110 against the inner face of the outer connecting portion; inwardly folding tabs extending from the lower edges of the respective inner side portions; an intermediate cover flap extending from the lower edge of the inner front portion and folding over said tabs; a folding flap extending from the lower edge of the back portion and comprising an intermediate portion covering the cover flap, and a tucking portion adapted 115 to be tucked between said front portions; and means for closing the upper part of the container.

8. A collapsible container comprising a 120 back portion; outer and inner front por-

130

tions; side portions connecting the front portions with the back portion; a pouring closure at the upper edge of the inner and side portions and provided with longitudinal and diagonal scorings forming a middle section end sections; a sealing flap extending from the upper edge of said back portion covering said sections and adapted to be inserted between said front portions, and to dispose itself in the plane of the back portion; inwardly folding tabs extending from the lower part of the side portions; an intermediate cover flap extending from the lower part of the inner front portion and folding over said tabs; and a folding flap extending from the lower part of the back

portion and adapted to cover said cover flap and to be tucked between said front portions; said flaps being adapted to be disposed in the plane of said back portion, said middle section and said cover flap in the plane of said inner front portion, and said tabs and end sections in the planes of said side portions, whereby said side portions are adapted to be folded against said back portion and inner front portion respectively to permit the container to be folded flat.

EDWARD O. TINSLEY.
